UNITED STATES PATENT OFFICE.

JOHN ALGEN BELK, OF FEILDING, NEW ZEALAND.

FISH-PLATE FOR RAILWAYS.

No. 927,932.

Specification of Letters Patent. Patented July 13, 1909.

Application filed April 17, 1909. Serial No. 490,590.

To all whom it may concern:

Be it known that I, JOHN ALGEN BELK, subject of the King of Great Britain, residing at Feilding, New Zealand, have invented 5 a new and useful Improved Fish-Plate for Railways; and I do hereby declare the following to be a full, clear, and exact description of the same.

This invention relates to an improvement 10 in the fish plates used in railway construction. These, as hitherto formed, consist of a length of metal plate that is bolted to the sides of the rail ends and extends across the joints. These plates get worn along their 15 top edges by the wheels of the train running over them, with the consequence that they are caused to rattle. It is the custom to compensate for such wear by driving strips of iron in between the top of the plates and 20 the rail heads.

The present invention has been designed in order to do away with the use of these strips, and to provide for the plate being quickly tightened against rattling when 25 required.

In carrying out the invention, the fish plate is formed in two longitudinal portions, dovetailed together so as to be capable of sliding. The top portion is formed of nar- 30 row wedge shape longitudinally, so that when it wears, it may be tightened again by giving it a blow or two on one end with a hammer. The bottom portion alone is bolted to the rails.

35 Any two of the adjacent faces of the dove-tailed joint may be formed with teeth or serrations, or suitably roughened in such a manner as to allow the wedge portion being driven in one direction, but to prevent 40 any back slip.

In the accompanying drawings,—Figure 1 is a side elevation of a rail joint with the improved fish plate in position thereon. Fig. 2 is an end elevation of the same. Fig. 3 is 45 a back elevation of portion of the lower part of the fish plate.

The fish plate according to this invention, is formed of the two longitudinal portions A and B, such two portions being dovetailed 50 together as shown in Fig. 2, so that one shall be made capable of sliding upon the other. The lower portion B, constitutes the fish

plate proper, and is secured across the rail joint by the bolts C, in the usual manner. Its upper edge is made with a slight incline 55 toward one end, and the lower edge of the upper portion A is correspondingly inclined. This upper portion thus constitutes a wedge capable of sliding upon the lower portion, and of being jammed between the lower portion, and the underside of the rail head. Any 60 looseness may thus be prevented by tightening the upper wedge portion when required, by driving it longitudinally from its larger end.

The adjacent faces of the joint between the two portions A and B are preferably formed with small teeth or serrations *a* and *b*, thereon, such teeth being so shaped as to allow of the upper portion being tightened 70 but to prevent any backward slip or movement.

The form of dovetail joint between the two portions A and B may be of any ap- 75 proved design that will serve to prevent the upper wedge portion moving away from the rail side. In the drawings, it is shown as being a single dovetail or overlap.

What I do claim as my invention, and desire to secure by Letters Patent, is,—

1. A railway fish plate formed longitudinally of two portions fitted together one above the other with a dovetailed or overlapping sliding joint, the lower portion being adapted to be secured to the rails while the upper portion is shaped as a wedge, substantially 85 as specified.

2. A railway fish plate formed longitudinally of two portions fitted together one above the other with a dovetailed or overlapping sliding joint, and with the adjacent faces of such joint formed with serrations or projections thereon, the upper portion of the plate being also shaped longitudinally as a wedge, while the lower portion is adapted to 90 be secured to the rails, substantially as specified.

In testimony whereof I have signed this specification in the presence of two subscribing witnesses.

JOHN ALGEN BELK.
